COLLAPSING TAP

Royce M. Strickland, New Haven, Conn., assignor
to The Geometric Tool Company, New Haven,
Conn., a corporation of Connecticut

Application June 7, 1946, Serial No. 675,025

16 Claims. (Cl. 10—145)

1

The present invention relates to improvements in collapsing taps, i. e., thread-cutting devices which are adapted to form threads within cavities in objects, such as pipe fittings, etc., and which have a plurality of thread-cutting chasers projectable outwardly or settable for a thread-cutting operation, and which are also releasable or collapsible inwardly, to be disengaged from the threads just cut.

One of the objects of the present invention is to provide a superior collapsing tap characterized by strength and durability in use.

Another object of the present invention is to provide a device of the type described which is characterized by ease of setting and collapsing of its chasers.

A further object of the present invention is to provide a collapsing tap having a superior construction and arrangement of parts whereby the chasers may be released for removal and replacement.

Still another object of the present invention is to provide a superior collapsing tap combining strength and wear-resistance with compactness.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a view in side elevation of one form of collapsing tap embodying the present invention and shown as set in readiness to cut threads;

Fig. 2 is a view thereof in front elevation, but on a larger scale;

Fig. 3 is a view of the collapsing tap in rear elevation;

Fig. 4 is a broken central-longitudinal sectional view taken on the line 4—4 of Fig. 2;

Fig. 5 is a similar view but taken on the line 5—5 of Fig. 2;

Fig. 6 is a transverse sectional view taken on the line 6—6 of Fig. 4;

Fig. 7 is a similar view taken on the line 7—7 of Fig. 4;

Fig. 8 is a broken longitudinal sectional view taken on the line 8—8 of Fig. 3;

Fig. 9 is a perspective view of the coupling-member;

Fig. 10 is a similar view of the releasing-plunger;

Fig. 11 is a similar view of the assembly comprising the operating-sleeve, chaser-retracting

2

plungers and latch-member, together with one of the latch-releasing balls;

Fig. 12 is a perspective view of the latch-member;

Fig. 13 is a broken longitudinal sectional view corresponding to Fig. 4, but showing the parts in the positions which they assume when the chasers are retracted to disengage them from the work just threaded; and

Fig. 14 is a broken detail sectional view corresponding to the upper portion of Fig. 8 but showing the releasing-plunger moved forwardly into its releasing position, and showing the operating-sleeve and the tripping-sleeve moved rearwardly into position to effect the full release of the chasers, whereby the latter may be removed from the structure.

The particular collapsing tap chosen for illustration in the accompanying drawings for purposes of making clear a preferred form of the present invention, includes a body-member or chaser-carrying member generally designated by the reference character 15 and generally of cylindrical form. The said body-member includes a rearwardly-projecting shank 16 by means of which the collapsing tap is adapted to be mounted in the turret of a screw machine or other suitable support.

Adjacent its forward end, the body-member 15 is slightly enlarged to provide a head-portion 17 and terminates at its forward end in a nose-portion 18 of substantially the same diameter as the main portion of the body-member including its shank 16. Secured against the forward end of the nose-portion 18 is a cap 19 held in place by means of screws 20.

The forward portion of the body-member 15 is formed with a forwardly-opening axial guide-recess 21 of cylindrical form throughout the major portion of its length, and in which is adapted to reciprocate a chaser-operating plunger 22. At its forward end, the said chaser-operating plunger is formed with four (more or less) chaser-operating arms 23 which extend substantially radially and also in a direction parallel with the longitudinal axis of the plunger itself. Each of the arms 23 is formed on one of its side faces with a coupling-rib 24 which is forwardly and inwardly inclined, as is especially well shown in Fig. 5.

Engaging with the inclined outer edge of each of the chaser-operating arms 23, is the inclined inner end of one of four similar chasers 25, each of which is provided with an inclined coupling-rib 26 slidably fitting beneath the coupling-rib

24 of its complemental chaser-operating arm 23. Each of the said chasers 25 is formed upon its outer edge with thread-cutting teeth 27 and is mounted for movement in a substantially-radial direction in one of four corresponding and equidistantly-spaced guide-slots 28 formed partly in the head-portion 17 and nose-portion 18 of the body-member 15 and extending part way into the cap 19, as is indicated in Fig. 5.

Mounted upon the body-member 15 just to the rear of its head-portion 17 is a reciprocating operating-sleeve 29 of substantially-cylindrical exterior form and terminating at its rear in a radially-extending annular flange 30. Mounted in turn upon the exterior of the operating-sleeve 29 is a tripping-sleeve 31 having its forward portion sized interiorly to reciprocate with a smooth sliding fit upon the periphery of the forward or main portion of the operating-sleeve 29 and having its rear end recessed to accommodate and slide upon the periphery of the annular flange 30 at the rear of the said operating-sleeve.

At the junction of the main portion of its interior periphery with the enlarged rear portion thereof, the tripping-sleeve 31 is formed with a rearwardly-facing stop-shoulder 32 which is adapted to engage with a stop-screw 33 (Fig. 8) mounted in the annular flange 30 of the operating-sleeve 29 and extending in a direction parallel with the longitudinal axis of the device. For the purpose of holding the stop-screw 33 in a given position of adjustment, a coaxial lock螺丝 34 is also threaded into the flange 30 so as to impinge against the rear end of the said stop-screw, as is indicated in Fig. 8.

The tripping-sleeve 31 above referred to may be moved rearwardly relative to the operating-sleeve 29 upon which it slides in several different ways such, for instance, as by a suitable stop or abutment extending into an annular groove 31a or by means of a pivotal lever-handle 35. In the manner which will hereinafter appear, the lever-handle 35 will serve the dual purpose of resetting the chasers 25, and of effecting their release for radial inward movement.

The lever-handle 35 above referred to extends substantially radially with respect to the tap structure and is pivoted intermediate its respective opposite ends upon a removable pivot-pin 36 carried by the tripping-sleeve 31 and extending across a clearance-passage 37 in the said tripping-sleeve. The inwardly-projecting portion of the lever-handle 35 extends through a longitudinal clearance-slot 38 formed in the operating-sleeve 29, as is shown in Figs. 4 and 13.

The inner end of the lever-handle 35 is spherically contoured and extends and rocks in a socket 39 formed in the portion of the body-member 15 lying within the said operating-sleeve 29. For the purpose of limiting the tripping-sleeve 31 to movement in an axial direction, the inner periphery of the forward portion of the said tripping-sleeve is formed with a longitudinal keyway 40 into which extends a key 41 (Figs. 4 and 13) mounted in and extending beyond the outer periphery of the operating-sleeve 29.

The operating-sleeve 29 is, in turn, limited to movement in an axial direction by means of a key 42 mounted in and projecting beyond the outer periphery of the body-member 15 and having sliding engagement with a longitudinal clearance-notch 43 (Fig. 5) formed in the forward portion of the said operating-sleeve.

The operating-sleeve 29 is yieldingly urged to move rearwardly relative to the body-member

15 by means of two (more or less) chaser-retracting springs 44-44, each of which is mounted in one of two similar sockets 45-45 formed in the operating-sleeve 29. The said sockets extend in substantial parallelism with the longitudinal axis of the device and open through the forward face of the operating-sleeve, as is shown in Fig. 5. Each of the chaser-retracting springs 44-44 is seated at its rear end against the end wall of its complemental socket 45 and presses at its forward end against the front wall of the adjacent one of two corresponding cup-shaped plungers 46-46. Each of the said plungers is mounted for reciprocation in one of the sockets 45-45 and impinges at its forward end against the rear face of the head-portion 17 of the body-member 15, as is indicated in Fig. 5.

The interior of the body-member 15 is formed in its forward portion with four longitudinal clearance-grooves 47 respectively registering with and adapted to receive the plate-like chaser-operating arms 23 of the chaser-operating plunger 22.

Adjacent its rear end, the chaser-operating plunger 22 is formed with a transverse coupling-notch 48 which receives the inner end of a coupling-leg 49 projecting radially inwardly from the central portion of a T-shaped adjustable coupling-member 50. The said coupling-leg extends through a relatively-long longitudinal clearance-slot 51 formed in the body-member 15. At its inner end, the said clearance-slot intersects the longitudinal guide-recess 21, and at its outer end intersects the periphery of the said body-member.

The coupling-leg 49 of the coupling-member 50 also projects through the clearance-slot 43 before referred to and in which the key 42 also moves. The said clearance-slot 43 communicates at its inner end with the clearance-slot 51 in the body-member 15, and communicates at its outer end with a longitudinal passage 53 formed in the operating-sleeve 29. The said passage 53 extends completely through the operating-sleeve 29 from the front to the rear thereof, and is of cylindrical form to snugly receive the cylindrical end portions of the head or cross of the T-shaped coupling-member 50 before referred to, in the manner indicated in Fig. 5.

The T-shaped coupling-member 50 is held against axial movement relative to the operating-sleeve 29, by means of a front adjusting-screw 54 and a rear adjusting-screw 55. The said adjusting-screws 54 and 55 are threaded respectively into the front and rear portions of the operating-sleeve 29 at a point slightly circumferentially displaced with respect to the longitudinal passage 53 and respectively thrust against seats 56 and 57. The seats 56 and 57 are formed in the coupling-member 50 and respectively face forwardly and rearwardly, and when the adjusting-screws 54 and 55 are respectively seated thereagainst, the coupling-member 50 is clamped between the two said screws. In this manner, the said coupling-member is rigidly held so as to normally form a rigid feature of the operating-sleeve 29, to thus transmit the movement of the latter to the chaser-operating plunger 22 within the body-member 15.

For the purpose of releasably holding the operating-sleeve 29 in its forward position against the tension of the chaser-retracting springs 44-44, a plate-like latch-member 58 is employed. The said latch-member is mounted for movement toward and away from the central longitudinal axis of the structure in a transverse guide-groove

59 formed in the forward portion of the flange 30 at the rear of the operating-sleeve 29.

The outer portion of the latch-member 58 is curved to substantially conform to the curvature of the outer periphery of the flange 30 at the rear of the operating-sleeve 29 while its inner edge is substantially straight save for its central portion, which is curved to substantially conform to the exterior periphery of the adjacent portion of the body-member 15. The central portion of the inner edge of the latch-member 58 is adapted to project into a transverse latching-groove 60 formed in the body-member 15 at a point substantially-diametrically-opposite the socket 39 in which the hand-lever 35 engages. The rear wall of the latching-groove 60 just referred to, constitutes a forwardly-facing latching-abutment 61 which is adapted to be engaged by the central portion of the rear face of the latch-member 58.

The latch-member 58 above referred to, is yieldingly urged inwardly to engage the central inner portion of its rear face with the latching-abutment 61, by means of two helical latch-springs 62—62 fitting into suitable sockets in the said latch-member, as is shown in Fig. 7, the said latch-springs respectively having ball-bearings 63—63 interposed between their outer ends and the inner periphery of the rear portion of the tripping-sleeve 31, as shown in Fig. 7.

For the purpose of forcing the latch-member 58 outwardly to disengage its central portion from the latching-abutment 61, the said latch-member is formed adjacent the respective opposite ends of its inner edge with forwardly-and-outwardly-inclined surfaces 64—64 on which respectively rest latch-releasing balls 65—65. The latch-releasing balls 65—65 just referred to are respectively mounted for movement in a direction parallel with the longitudinal axis of the device, in rearwardly-opening cylindrical sockets 66—66 formed in the rear portion of the operating-sleeve 29 and mainly in its annular flange 30.

The rear ends of the sockets 66—66 are suitably plugged to exclude dirt, while the forward portions of each of the sockets break through the forward face of the annular flange 30. By this arrangement, the latch-releasing ball 65 in a given socket may assume a position in which it may be engaged by the rearwardly-facing stop-shoulder 32 within the rear portion of the tripping-sleeve 31. Thus, in addition to serving as a stop-shoulder as before described, the surface 32 will also serve in a manner as will hereinafter appear, as a tripping-shoulder to force the latch-releasing balls 65—65 rearwardly in their respective sockets 66—66. When so moved, the said balls will ride against the inclined surfaces 64—64 of the said latch-member and thus force the latter radially outwardly to disengage the central inner portion of its rear face from the latching-abutment 61 of the body-member 15.

For the purpose of normally limiting the rearward travel of the operating-sleeve 29 under the urge of the chaser-retracting springs 44, a stop-ball or stop-member 67 is employed, as is indicated in Figs. 8 and 14. The said stop-ball is mounted for movement in a radial direction in a closely-fitting radial clearance-passage 68 formed in the operating-sleeve 29, and at its inner end intersecting the inner periphery of the said operating-sleeve and at its outer end intersecting a longitudinal passage 69 also formed in the said operating-sleeve 29. Mounted for reciprocation in the passage 69 just referred to, is a releasing-plunger 70 which normally projects beyond the

rear face of the operating-sleeve 29. The said releasing-plunger is mainly of cylindrical form in cross section and is formed in its inner face with a longitudinal groove 71 in which the stop-ball 67 is adapted to ride, and with a clearance-pocket 72 adapted under certain conditions to accommodate a part of the said stop-ball 67.

The releasing-plunger 70 above described, is normally yieldingly urged rearwardly to engage the curved forward wall of its longitudinal groove 71 with the stop-ball 67, by means of a helical spring 73 located in the forward portion of the longitudinal passage 69 in the operating-sleeve 29. The rear end of the said spring 73 thrusts rearwardly against the adjacent end of the releasing-plunger 70, while its forward end engages with the rear face of a spring-seat 74 mounted in the forward portion of the longitudinal passage 69. The said spring-seat is cut away on the forward portion of one side to provide it with a forwardly-facing stop-shoulder 75. The said stop-shoulder is engaged with the rear face of the head 76 of a stop-screw having a shank 77 threaded into the forward portion of the operating-sleeve 29. The head 76 of the said stop-screw is mainly seated in a forwardly-opening recess 78 formed in the forward face of the operating-sleeve 29 and partly projects into an arcuate recess 79 formed in the forward inner corner of the tripping-sleeve 31. The recess 79 is concentric with the recess 78, as is apparent from Fig. 2. As thus constructed and arranged, the rear face of the head 76 of the stop-screw serves to limit the forward movement of both the spring-seat 74 and the tripping-sleeve 31 with respect to the operating-sleeve 29.

The inner portion of the stop-ball 67 above referred to, normally projects into a longitudinal groove 80 formed in the periphery of the body-member 15 and having its curved rear wall engaged by the stop-ball 67 to normally (but releasably) limit the rearward travel of the operating-sleeve 29 under the urge of its chaser-retracting springs 44—44.

45

Operation

For purposes of description let it be assumed that it is desired to internally thread an object by rotating such object while the collapsing tap is mounted (by means of its shank-portion 16) in the turret of a screw machine or other suitable holder.

Let it further be assumed that the collapsing tap is set or cocked as is shown in Figs. 1 to 8 inclusive. To effect the setting just referred to, the lever-handle 35 will have been manually pushed forwardly to thereby similarly shift the tripping-sleeve 31 in the same direction and thus cause the latter to also force the operating-sleeve 29 forwardly until the central portion of the inner rear corner of the plate-like latch-member 58 has been brought into registry with the latching-abutment 61 in the body-member 15 and has moved radially inwardly to engage with the said latching-abutment.

The described forward movement of the operating-sleeve 29 into its latched position will similarly move the coupling-member 50 and hence will also move the chaser-operating plunger 22 forwardly. The forward movement of the chaser-operating plunger will cause the inclined chaser-operating arms 23 to force the chasers 25 radially outwardly into position to cut the desired thread within an object such, for instance, as a pipe-fitting or the like.

As just above described, the forward movement of the tripping-sleeve 31, operating-sleeve 29, etc., was effected by manually forcing the upper end of the lever-handle 35 forwardly. The same movement may be accomplished, however, by any suitable yoke or the like engaged with the annular groove 31a in the periphery of the said tripping-sleeve.

After the desired length of thread has been cut by the chasers 25, the collapsing tap may be tripped to radially retire its said chasers 25 in one of several modes.

For instance, the lever-handle 35 may be manually swung rearwardly to thereby slide the tripping-sleeve to which it is pivoted, rearwardly relative to the operating-sleeve 29.

Still another mode of effecting the rearward movement of the tripping-sleeve would be to have its forward end or an extension thereof, engaged with a suitable abutment which would halt the forward travel of the said tripping-sleeve, while the remainder of the structure is still advancing during the threading operation, to thereby effect relative rearward movement of the said tripping-sleeve with respect to the structure by which it is carried. The annular groove 31a of the said tripping-sleeve may also be utilized to arrest the forward movement of the tripping-sleeve, as just described.

When the tripping-sleeve 31 is moved rearwardly relative to the operating-sleeve 29 (or equivalently when the forward movement of the tripping-sleeve is halted and the said operating-sleeve moves forwardly relative to the said tripping-sleeve), the rearwardly-facing annular stop-shoulder 32 within the said tripping-sleeve will force the latch-releasing balls 65—65 rearwardly along the inclined surfaces 64—64 of the latch-member 58, thereby forcing the said latch-member radially outwardly against the tension of the latch-springs 62—62. As soon as the curved central portion of the upper rear edge of the said latch-member clears the outer corner of the latching-abutment 61 of the body-member 15, the operating-sleeve 29 will be free to snap rearwardly under the urge of the chaser-retracting springs 44—44.

Through the intermediary of the coupling-member 50, the rearward movement of the operating-sleeve 29 will effect the similar movement of the chaser-operating plunger 22. This latter movement will cause the inclined coupling-ribs 24 and the similarly inclined and inter-engaging coupling-ribs 26 of the chasers 25, to positively move the said chasers radially inwardly to disengage the thread-cutting teeth 27 thereof from the article which has just been threaded.

The relative rearward movement of the operating-sleeve 29 with respect to the body-member 15 will be effected by the urge of the chaser-retracting springs 44 and will be checked by the engagement of the stop-ball 67 with the stop-abutment formed by the rear end of the longitudinal groove 80 in the body-member 15. Similarly, the rearward movement of the tripping-sleeve 31 relative to the operating-sleeve 29 upon which it is mounted, will be limited by the engagement of the stop-shoulder 32 of the said tripping-sleeve with the stop-screw 33 carried at the rear of the operating-sleeve 29.

In rare instances where the thread-cutting teeth 27 of the chasers 25 are so tightly engaged with the work-piece being threaded that the chaser-retracting springs 44 are not sufficiently powerful to effect the rearward movement of the operat-

ing-sleeve 29 and connected parts to thus retract the said chasers, the engagement of the stop-shoulder 32 of the tripping-sleeve 31 with the stop-screw 33 will cause the said tripping-sleeve to positively move the operating-sleeve 29 rearwardly and thus positively retract the chasers 25.

Should it be desired to adjust the diameter of the threads to be formed by the thread-cutting teeth 27 when the chasers 25 are in their projected positions, the chaser-operating plunger 22—and hence the chasers 25—may be adjusted by turning the front and rear adjusting-screws 54 and 55 to shift the coupling-member 50 (and hence also the plunger 22) in the desired direction with respect to the operating-sleeve 29. A rearward shifting of the coupling-member 50 will cause a lesser-dia-metered thread to be cut, whereas an adjustment of the said coupling-member 50 in a forward direction will cause a larger-dia-metered thread to be cut by the chasers 25.

When the chaser-operating plunger 22 is moved rearwardly to effect the retirement of the chasers 25, as previously described, the said plunger does not move sufficiently rearwardly to disengage its coupling-ribs 24 from the coupling-ribs 26 of the chasers. Therefore, when it is desired to remove the chasers 25 for purposes of replacement or other reasons and without removing the cap 19, the releasing-plunger 70 may be moved forwardly, as is indicated in Fig. 14.

When the releasing-plunger 70 is moved forwardly as above referred to, its clearance-pocket 72 will be brought into a position wherein the stop-ball 67 may ride upwardly thereinto and thus clear it of the stop-abutment formed by the curved rear end of the longitudinal groove 80 in the body-member 15. When this occurs the operating-sleeve 29 will be forced rearwardly (beyond its normal chaser-returning position) by the chaser-retracting springs 44—44 a distance sufficient to fully disengage the chaser-operating arms 23 of the plunger 22 from the chasers 25, as is shown in Fig. 14. The said chasers may now be extracted radially from the radial guide-slots 28 in the body-member 15.

When as above described, the operating-sleeve 29 is permitted to move rearwardly sufficiently to permit the removal of the chasers 25, the rearward movement referred to will be limited by the engagement of the rear edge of the radial coupling-leg 49 of the coupling-member 50 with the rear wall of the clearance-slot 51 in the body-member 15.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A collapsing tap having a plurality of advanceable and retractable thread-cutting chasers and including in combination: a chaser-carrying member having a plurality of substantially-radial chaser-guides and formed with a forwardly-facing latching-abutment; a plurality of thread-cutting chasers carried by the said chaser-carrying member and movable substantially radially in the chaser-guides thereof; an operating-sleeve mounted for axial movement upon the said chaser-carrying member and formed with a sub-

stantially-radial latch-receiving passage and with transmitter-guiding means extending in substantial parallelism with the longitudinal axis of the tap; chaser-operating means operatively connecting the said operating-sleeve with the said chasers; spring-means urging the said operating-sleeve rearwardly; a latch-member mounted for movement in a substantially-radial direction in the latch-receiving passage of the said operating-sleeve and engageable with and disengageable from the latching-abutment of the said chaser-carrying member, the said latch-member being provided with an inclined releasing-surface sloping forwardly and laterally outwardly away from the longitudinal axis of the tap; a rolling transmitting-member rollable in the transmitter-guiding means of the said operating-sleeve in a direction substantially longitudinal of the latter; and a tripping-sleeve axially movable upon the said operating-sleeve and having a rearwardly-facing abutment engageable with the said transmitting-member to roll the same rearwardly in the transmitter-guiding means of the said operating-sleeve and along the inclined releasing-surface of the said latch-member to force the latter out of engagement with the latching-abutment of the said chaser-carrying member.

2. A collapsing tap having a plurality of advanceable and retrievable thread-cutting chasers and including in combination: a chaser-carrying member having a plurality of substantially-radial chaser-guides and formed with a forwardly-facing latching-abutment; a plurality of thread-cutting chasers carried by the said chaser-carrying member and movable substantially radially in the chaser-guides thereof; an operating-sleeve mounted for axial movement upon the said chaser-carrying member and formed with a substantially-radial latch-receiving passage and with two laterally-spaced-apart transmitter-guiding means both extending in substantial parallelism with the longitudinal axis of the tap; chaser-operating means operatively connecting the said operating-sleeve with the said chasers; spring-means urging the said operating-sleeve rearwardly; a latch-member mounted for movement in a substantially-radial direction in the latch-receiving passage of the said operating sleeve and engageable with and disengageable from the latching-abutment of the said chaser-carrying member, the said latch-member being provided with two laterally-spaced-apart inclined releasing surfaces each sloping forwardly and laterally outwardly away from the longitudinal axis of the tap and respectively registering with the transmitter-guiding means in the said chaser-carrying member; two rolling transmitting-members respectively movable in the transmitter-guiding means of the said operating-sleeve in a direction substantially longitudinal of the latter; and a tripping-sleeve axially movable upon the said operating-sleeve and having rearwardly-facing abutments respectively engageable with the two said transmitting-members to roll the same rearwardly in their complemental transmitter-guiding means of the said operating-sleeve and respectively along the inclined releasing surfaces of the said latch-member to force the latter out of engagement with the latching-abutment of the said chaser-carrying member.

3. A collapsing tap having a plurality of advanceable and retrievable thread-cutting chasers and including in combination: a chaser-carrying member having a plurality of substantially-radial chaser-guides and formed with a forwardly-fac-

ing latching-abutment; a plurality of thread-cutting chasers carried by the said chaser-carrying member and movable substantially radially in the chaser-guides thereof; an operating-sleeve mounted for axial movement upon the said chaser-carrying member and formed with a substantially-radial latch-receiving passage and with a ball-guiding passage extending in substantial parallelism with the longitudinal axis of the tap; chaser-operating means operatively connecting the said operating-sleeve with the said chasers; spring-means urging the said operating-sleeve rearwardly; a latch-member mounted for movement in a substantially-radial direction in the latch-receiving passage of the said operating-sleeve and engageable with and disengageable from the latching-abutment of the said chaser-carrying member, the said latch-member being provided with an inclined releasing-surface sloping forwardly and laterally outwardly away from the longitudinal axis of the tap; a transmitting-ball rollable in the ball-guiding passage in the said chaser-operating sleeve in a direction substantially longitudinal of the latter; and a tripping-sleeve axially movable upon the said operating-sleeve and having a rearwardly-facing abutment engageable with the said transmitting-ball to roll the same rearwardly in the ball-guiding passage in the said operating-sleeve and along the inclined releasing-surface of the said latch-member to force the latter out of engagement with the latching-abutment of the said chaser-carrying member.

4. A collapsing tap having a plurality of advanceable and retrievable thread-cutting chasers and including in combination: a chaser-carrying member having a plurality of substantially-radial chaser-guides and formed with a forwardly-facing latching-abutment; a plurality of thread-cutting chasers carried by the said chaser-carrying member and movable substantially radially in the chaser-guides thereof; an operating-sleeve mounted for axial movement upon the said chaser-carrying member and formed with a substantially-radial latch-receiving passage and with two laterally-spaced-apart ball-guiding passages both extending in substantial parallelism with the longitudinal axis of the tap; chaser-operating means operatively connecting the said operating-sleeve with the said chasers; spring-means urging the said operating-sleeve rearwardly; a latch-member mounted for movement in a substantially-radial direction in the latch-receiving passage of the said operating-sleeve and engageable with and disengageable from the latching-abutment of the said chaser-carrying member, the said latch-member being provided with two laterally-spaced-apart inclined releasing-surfaces each sloping forwardly and laterally outwardly away from the longitudinal axis of the tap and respectively registering with the ball-guiding passages in the said chaser-carrying member; two transmitting-balls respectively rollable in the ball-guiding passages in the said chaser-operating sleeve in a direction substantially longitudinal of the latter; and a tripping-sleeve axially movable upon the said operating-sleeve and having rearwardly-facing abutments respectively engageable with the said transmitting-balls to roll the same rearwardly in the ball-guiding passages in the said operating-sleeve and along the inclined releasing-surface of the said latch-member to force the latter out of engagement with the latching-abutment of the said chaser-carrying member.

5. A collapsing tap having a plurality of advanceable and retractable thread-cutting chasers and including in combination: a chaser-carrying member having a plurality of substantially-radial chaser-guides and having a longitudinal passage in its interior, the said chaser-carrying member being formed with a clearance-slot leading outwardly from the said longitudinal passage to the outer surface of the member; a plurality of thread-cutting chasers carried by the said chaser-carrying member and movable substantially radially in the chaser-guides thereof; a chaser-operating plunger movable in the longitudinal passage in the said chaser-carrying member and operatively connected to the said chasers to advance and retire the same; an operating-sleeve mounted for axial movement upon the said chaser-carrying member and formed with a longitudinal cylindrical guide passage communicating laterally with the clearance-slot in the said chaser-carrying member; a coupling-member having a cylindrical portion closely fitting and movable in the longitudinal guide passage in the said operating-sleeve and having a coupling-leg extending laterally inwardly through the clearance-slot in the said chaser-carrying member and operatively connected to the said chaser-operating plunger; adjusting-means carried by the said operating-sleeve and engaging the said coupling-member to shift it longitudinally relative to the operating-sleeve and hence also correspondingly shift the said chaser-operating plunger; spring-means urging the said operating-sleeve in an axial direction; and latch-means releasably coupling the said operating-sleeve to the said chaser-carrying member to releasably hold the former against axial movement under the urge of the said spring-means, the said latch-means being independent of and unaffected by the adjustment of the said coupling-member.

6. A collapsing tap having a plurality of advanceable and retractable thread-cutting chasers and including in combination: a chaser-carrying member having a plurality of substantially-radial chaser-guides and having a longitudinal passage in its interior the said chaser-carrying member being formed with a clearance-slot leading outwardly from the said longitudinal passage to the outer surface of the member; a plurality of thread-cutting chasers carried by the said chaser-carrying member and movable substantially radially in the chaser-guides thereof; a chaser-operating plunger movable in the longitudinal passage in the said chaser-carrying member and operatively connected to the said chasers to advance and retire the same; an operating-sleeve mounted for axial movement upon the said chaser-carrying member and formed with a longitudinal guide passage communicating laterally with the clearance-slot in the said chaser-carrying member; a T-shaped coupling-member having a body closely fitting and movable in the longitudinal guide passage in the said operating-sleeve and having a coupling-leg intermediate its opposite ends and extending laterally inwardly through the clearance-slot in the said chaser-carrying member the said coupling-leg being operatively connected to the said chaser-operating plunger; adjusting-means carried by the said operating-sleeve and engaging the said T-shaped coupling-member to shift it longitudinally relative to the operating-sleeve and hence also correspondingly shift the said chaser-operating plunger; spring-means urging the said operating-sleeve in an axial direction; and latch-means

releasably coupling the said operating-sleeve to the said chaser-carrying member to releasably hold the former against axial movement under the urge of the said spring-means the said latch-means being independent of and unaffected by the adjustment of the said T-shaped coupling-member.

7. A collapsing tap having a plurality of advanceable and retractable thread-cutting chasers and including in combination: a chaser-carrying member having a plurality of substantially-radial chaser-guides and having a longitudinal passage in its interior, the said chaser-carrying member being formed with a clearance-slot leading outwardly from the said longitudinal passage to the outer surface of the member; a plurality of thread-cutting chasers carried by the said chaser-carrying member and movable substantially radially in the chaser-guides thereof; a chaser-operating plunger movable in the longitudinal passage in the said chaser-carrying member and operatively connected to the said chasers to advance and retire the same; an operating-sleeve mounted for axial movement upon the said chaser-carrying member and formed with a longitudinal cylindrical guide passage communicating laterally with the clearance-slot in the said chaser-carrying member; a coupling-member having a cylindrical body closely fitting and movable in the longitudinal guide passage in the said operating-sleeve and having a coupling-leg extending laterally inwardly through the clearance-slot in the said chaser-carrying member and operatively connected to the said chaser-operating plunger; a pair of adjusting-screws carried by the said operating-sleeve and respectively engaging opposite ends of the body of the said coupling-member to shift it longitudinally relative to the operating-sleeve and hence also correspondingly shift the said chaser-operating plunger; spring-means urging the said operating-sleeve in an axial direction; and latch-means releasably coupling the said operating-sleeve to the said chaser-carrying member to releasably hold the former against axial movement under the urge of the said spring-means the said latch-means being independent of and unaffected by the adjustment of the said coupling-member.

8. A collapsing tap having a plurality of advanceable and retractable thread-cutting chasers and including in combination: a chaser-carrying member having a plurality of substantially-radial chaser-guides and having a longitudinal passage in its interior the said chaser-carrying member being formed with a clearance-slot leading outwardly from the said longitudinal passage to the outer surface of the member; a plurality of thread-cutting chasers carried by the said chaser-carrying member and movable substantially radially in the chaser-guides thereof; a chaser-operating plunger movable in the longitudinal passage in the said chaser-carrying member and operatively connected to the said chasers to advance and retire the same; an operating-sleeve mounted for axial movement upon the said chaser-carrying member and formed with a longitudinal passage communicating laterally with the clearance-slot in the said chaser-carrying member; a T-shaped coupling-member movable in the longitudinal passage in the said operating-sleeve and having a coupling-leg intermediate its opposite ends and extending laterally inwardly through the clearance-slot in the said chaser-carrying member the said coupling-leg being operatively connected to the said chaser-operating

plunger; a pair of adjusting-screws carried by the said operating-sleeve and respectively engaging opposite end portions of the said T-shaped coupling-member to shift it longitudinally relative to the operating-sleeve and hence also correspondingly shift the said chaser-operating plunger; spring-means urging the said operating-sleeve in an axial direction; and latch-means releasably coupling the said operating-sleeve to the said chaser-carrying member to releasably hold the former against axial movement under the urge of the said spring-means the said latch-means being independent of and unaffected by the adjustment of the said T-shaped coupling-member.

9. A thread-cutting device having a plurality of advanceable and retrivable thread-cutting chasers and including in combination: a chaser-carrying member having a plurality of substantially-radial chaser-guides and provided at its periphery with a stop-abutment; a plurality of thread-cutting chasers carried by the said chaser-carrying member and movable substantially radially in the chaser-guides thereof; an operating-sleeve mounted for axial movement upon the said chaser-carrying member and formed with a substantially-longitudinal plunger-receiving passage located adjacent the stop-abutment of the said chaser-carrying member but spaced outwardly therefrom, the said operating-sleeve also being formed with a lateral guide-passage extending between the inner periphery of the operating-sleeve and the plunger-receiving passage therein; a stop-member mounted for movement in the lateral guide-passage in the said operating-sleeve and engageable with the stop-abutment of the chaser-carrying member to limit the movement of the operating-sleeve; a releasing-plunger mounted for reciprocation in the plunger-receiving passage of the said operating-sleeve and having a portion normally overlying the outer portion of the said stop-member to releasably hold the same against outward movement and compel the stop-member to engage with the said stop-abutment to limit the travel of the operating-sleeve, the said releasing-plunger being provided with a clearance-portion movable into registry with the said stop-member to permit the latter to move outwardly clear of the stop-abutment of the chaser-carrying member; spring-means urging the said operating-sleeve in an axial direction with respect to the said chaser-carrying member; and releasable latch-means releasably restraining the said operating-member against axial movement under the urge of the said spring-means.

10. A thread-cutting device having a plurality of advanceable and retrivable thread-cutting chasers and including in combination: a chaser-carrying member having a plurality of substantially-radial chaser-guides and provided at its periphery with a stop-abutment; a plurality of thread-cutting chasers carried by the said chaser-carrying member and movable substantially radially in the chaser-guides thereof; an operating-sleeve mounted for axial movement upon the said chaser-carrying member and formed with a substantially-longitudinal plunger-receiving passage located adjacent the stop-abutment of the said chaser-carrying member but spaced outwardly therefrom, the said operating-sleeve also being formed with a lateral guide-passage extending between the inner periphery of the operating-sleeve and the plunger-receiving passage therein; a stop-ball mounted for movement in the lateral

guide-passage in the said operating-sleeve and engageable with the stop-abutment of the chaser-carrying member to limit the movement of the operating-sleeve; a releasing-plunger mounted for reciprocation in the plunger-receiving passage of the said operating-sleeve and having a portion normally overlying the outer portion of the said stop-ball to releasably hold the same against outward movement and compel the stop-ball to engage with the said stop-abutment to limit the travel of the operating-sleeve, the said releasing-plunger being provided with a clearance-portion movable into registry with the said stop-ball to permit the latter to move outwardly clear of the stop-abutment of the chaser-carrying member; spring-means urging the said operating-sleeve in an axial direction with respect to the said chaser-carrying member; and releasable latch-means releasably restraining the said operating-member against axial movement under the urge of the said spring-means.

11. A thread-cutting device having a plurality of advanceable and retrivable thread-cutting chasers and including in combination: a chaser-carrying member having a plurality of substantially-radial chaser-guides and provided at its periphery with a stop-abutment; a plurality of thread-cutting chasers carried by the said chaser-carrying member and movable substantially radially in the chaser-guides thereof; an operating-sleeve mounted for axial movement upon the said chaser-carrying member and formed with a substantially-longitudinal plunger-receiving passage located adjacent the stop-abutment of the said chaser-carrying member but spaced outwardly therefrom, the said operating-sleeve also being formed with a lateral guide-passage extending between the inner periphery of the operating-sleeve and the plunger-receiving passage therein; a stop-member mounted for movement in the lateral guide-passage in the said operating-sleeve and engageable with the stop-abutment of the chaser-carrying member to limit the movement of the operating-sleeve; a releasing-plunger mounted for reciprocation in the plunger-receiving passage of the said operating-sleeve and having a portion normally overlying the outer portion of the said stop-member to releasably hold the same against outward movement and compel the stop-member to engage with the said stop-abutment to limit the travel of the operating-sleeve, the said releasing-plunger being provided with a clearance-portion movable into registry with the said stop-member to permit the latter to move outwardly clear of the stop-abutment of the chaser-carrying member; spring-means urging the said releasing-plunger in a direction to yieldingly hold its clearance-portion out of registry with the said stop-member; spring-means urging the said operating-sleeve in an axial direction with respect to the said chaser-carrying member; and releasable latch-means releasably restraining the said operating-member against axial movement under the urge of the said spring-means.

12. A thread-cutting device having a plurality of advanceable and retrivable thread-cutting chasers and including in combination: a chaser-carrying member having a plurality of substantially-radial chaser-guides and provided at its periphery with a stop-abutment; a plurality of thread-cutting chasers carried by the said chaser-carrying member and movable substantially radially in the chaser-guides thereof; an operating-sleeve mounted for axial movement upon

the said chaser-carrying member and formed with a substantially-longitudinal plunger-receiving passage located adjacent the stop-abutment of the said chaser-carrying member but spaced outwardly therefrom, the said operating-sleeve also being formed with a lateral guide-passage extending between the inner periphery of the operating-sleeve and the plunger-receiving passage therein; a stop-ball mounted for movement in the lateral guide-passage in the said operating-sleeve and engageable with the stop-abutment of the chaser-carrying member to limit the movement of the operating-sleeve; a releasing-plunger mounted for reciprocation in the plunger-receiving passage of the said operating-sleeve and having a portion normally overlying the outer portion of the said stop-ball to releasably hold the same against outward movement and compel the stop-ball to engage with the said stop-abutment to limit the travel of the operating-sleeve, the said releasing-plunger being provided with a clearance-portion movable into registry with the said stop-ball to permit the latter to move outwardly clear of the stop-abutment of the chaser-carrying member; spring-means urging the said releasing-plunger in a direction to yieldingly hold its clearance-portion out of registry with the said stop-ball; spring-means urging the said operating-sleeve in an axial direction with respect to the said chaser-carrying member; and releasable latch-means releasably restraining the said operating-member against axial movement under the urge of said spring-means.

13. A thread-cutting device having a plurality of advanceable and retrivable thread-cutting chasers and including in combination: a chaser-carrying member having a plurality of substantially-radial chaser-guides and formed in its periphery with a substantially-longitudinal groove having a forwardly-facing stop-abutment at its rear; a plurality of thread-cutting chasers carried by the said chaser-carrying member and movable substantially radially in the chaser-guides thereof; an operating-sleeve mounted for axial movement upon the said chaser-carrying member and formed with a substantially-longitudinal plunger-receiving passage located adjacent the longitudinal groove in the periphery of the said chaser-carrying member but spaced outwardly therefrom, the said operating-sleeve also being formed with a lateral guide-passage extending between the longitudinal groove in the said chaser-carrying member and the plunger-receiving passage in the operating-sleeve; a stop-member mounted for movement in the lateral guide-passage in the said operating-sleeve and engageable with the said stop-abutment to limit the movement of the operating-sleeve with respect to the chaser-carrying member, the said stop-member having a dimension in a radial direction exceeding the distance between the periphery of the said chaser-carrying member and the plunger-receiving passage in the said operating-sleeve; and a releasing-plunger mounted for reciprocation in the plunger-receiving passage of the said operating-sleeve and formed with a clearance-recess opening toward the periphery of the said chaser-carrying member, the said clearance-recess having a depth sufficient to accommodate the said stop-member when the releasing-plunger is moved longitudinally to register its said clearance-recess with the said stop-member and when the latter is moved outwardly

to ride upon the periphery of the said chaser-carrying member.

14. A thread-cutting device having a plurality of advanceable and retrivable thread-cutting chasers and including in combination: a chaser-carrying member having a plurality of substantially-radial chaser-guides and formed in its periphery with a substantially-longitudinal groove having a forwardly-facing stop-abutment at its rear; a plurality of thread-cutting chasers carried by the said chaser-carrying member and movable substantially radially in the chaser-guides thereof; an operating-sleeve mounted for axial movement upon the said chaser-carrying member and formed with a substantially-longitudinal plunger-receiving passage located adjacent the longitudinal groove in the periphery of the said chaser-carrying member but spaced outwardly therefrom, the said operating-sleeve also being formed with a lateral guide-passage extending between the longitudinal groove in the said chaser-carrying member and the plunger-receiving passage in the operating-sleeve; a stop-ball mounted for movement in the lateral guide-passage in the said operating-sleeve and engageable with the said stop-abutment to limit the movement of the operating-sleeve with respect to the chaser-carrying member, the said stop-ball having a diameter exceeding the distance between the periphery of the said chaser-carrying member and the plunger-receiving passage in the said operating-sleeve; and a releasing-plunger mounted for reciprocation in the plunger-receiving passage of the said operating-sleeve and formed with a clearance-recess opening toward the periphery of the said chaser-carrying member, the said clearance-recess having a depth sufficient to accommodate the said stop-ball when the releasing-plunger is moved longitudinally to register its said clearance-recess with the said stop-ball and when the latter is moved outwardly to ride upon the periphery of the said chaser-carrying member.

15. A thread-cutting device having a plurality of advanceable and retrivable thread-cutting chasers and including in combination: a chaser-carrying member having a plurality of substantially-radial chaser-guides and formed in its periphery with a substantially-longitudinal groove having a forwardly-facing stop-abutment at its rear; a plurality of thread-cutting chasers carried by the said chaser-carrying member and movable substantially radially in the chaser-guides thereof; an operating-sleeve mounted for axial movement upon the said chaser-carrying member and formed with a substantially-longitudinal plunger-receiving passage located adjacent the longitudinal groove in the periphery of the said chaser-carrying member but spaced outwardly therefrom, the said operating-sleeve also being formed with a lateral guide-passage extending between the longitudinal groove in the said chaser-carrying member and the plunger-receiving passage in the operating-sleeve; a stop-member mounted for movement in the lateral guide-passage in the said operating-sleeve and engageable with the said stop-abutment to limit the movement of the operating-sleeve with respect to the chaser-carrying member, the said stop-member having a dimension in a radial direction exceeding the distance between the periphery of the said chaser-carrying member and the plunger-receiving passage in the said operating-sleeve; and a releasing-plunger mounted for reciprocation in the plunger-receiving passage of the said operating-

sleeve and formed with a clearance-recess opening toward the periphery of the said chaser-carrying member, the said clearance-recess having a depth sufficient to accommodate the said stop-member when the releasing-plunger is moved longitudinally to register its said clearance-recess with the said stop-member and when the latter is moved outwardly to ride upon the periphery of the said chaser-carrying member; and spring-means urging the said releasing-plunger in a direction to yieldingly hold its clearance-recess out of registry with the said stop-member.

16. A thread-cutting device having a plurality of advanceable and retractable thread-cutting chasers and including in combination: a chaser-carrying member having a plurality of substantially-radial chaser-guides and formed in its periphery with a substantially-longitudinal groove having a forwardly-facing stop-abutment at its rear; a plurality of thread-cutting chasers carried by the said chaser-carrying member and movable substantially radially in the chaser-guides thereof; an operating-sleeve mounted for axial movement upon the said chaser-carrying member and formed with a substantially-longitudinal plunger-receiving passage located adjacent the longitudinal groove in the periphery of the said chaser-carrying member but spaced outwardly therefrom, the said operating-sleeve also being formed with a lateral guide-passage extending between the longitudinal groove in the said chaser-carrying member and the plunger-receiving passage in the operating-sleeve; a stop-ball mounted for

movement in the lateral guide-passage in the said operating-sleeve and engageable with the said stop-abutment to limit the movement of the operating-sleeve with respect to the chaser-carrying member, the said stop-ball having a diameter exceeding the distance between the periphery of the said chaser-carrying member and the plunger-receiving passage in the said operating-sleeve; a releasing-plunger mounted for reciprocation in the plunger-receiving passage of the said operating-sleeve and formed with a clearance-recess opening toward the periphery of the said chaser-carrying member, the said clearance-recess having a depth sufficient to accommodate the said stop-ball when the releasing-plunger is moved longitudinally to register its said clearance-recess with the said stop-ball and when the latter is moved outwardly to ride upon the periphery of the said chaser-carrying member; and spring-means urging the said releasing-plunger in a direction to yieldingly hold its clearance-recess out of registry with the said stop-ball.

ROYCE M. STRICKLAND.
